UNITED STATES PATENT OFFICE.

SYDNEY I. PRESCOTT, OF NEW YORK, N. Y., ASSIGNOR TO THE AMERICAN TOBACCO COMPANY, OF NEW YORK, N. Y., A CORPORATION OF NEW JERSEY.

REROLLING MECHANISM FOR CIGARETTE-SHELLS.

1,119,873.

Specification of Letters Patent.

Patented Dec. 8, 1914.

Application filed March 18, 1910. Serial No. 550,149.

To all whom it may concern:

Be it known that I, SYDNEY I. PRESCOTT, a citizen of the United States, residing at New York, county of New York, and State 5 of New York, have invented certain new and useful Improvements in Rerolling Mechanism for Cigarette-Shells, fully described and represented in the following specification and the accompanying drawings, forming a part of the same.

This invention relates to certain improvements in mechanism for making cigarette tubes containing mouthpieces, and more particularly to mechanism for re-rolling the 15 tubes after they have been formed and the mouthpieces inserted therein.

In the machines ordinarily employed in which mouthpieces are made and introduced into cigarette tubes, the tubes, after the insertion 20 of the mouthpieces, are usually subjected to the action of what is known as a rerolling mechanism by which the tubes having the inserted mouthpieces are subjected to a rolling action which tends to unroll the 25 coiled mouthpieces slightly so as to make them snugly fit the interior of the tubes. In these machines, there were no devices employed for positioning the tubes prior to being acted upon by the rerolling mechanism, so that it frequently happened that a 30 tube would be subjected to the action of the rerolling devices when its axis was not at right angles to its path of travel through the rerolling devices. The result of this was 35 that there was a tendency to unroll the mouthpiece spirally which caused the end of the mouthpiece blank to protrude slightly beyond the end of the tube or casing into which it was inserted, thus presenting an 40 unsightly appearance.

It is the object of this invention to provide an improved rerolling mechanism in which any tendency on the part of the mouthpiece to unroll spirally, thus causing 45 its end to protrude from the tube, is avoided.

With this and other objects not specifically referred to in view, the invention consists in certain constructions and in certain parts, improvements and combinations as 50 will be hereinafter fully described and then specifically pointed out.

In the accompanying drawings: Figure 1 is an end elevation of a mouthpiece rerolling mechanism, the figure also illustrating in 55 section certain parts of the machine for

forming the mouthpiece and inserting it into the tube. Fig. 2 is a vertical section taken through the rerolling mechanism shown in Fig. 1. Fig. 3 is a detail end elevation of the rerolling mechanism. Figs. 60 4, 5 and 6 are diagrammatic views illustrating the operation of the rerolling mechanism.

The cigarette shells which are to be operated on in the re-rolling mechanism may 65 be introduced into said mechanism in any suitable manner, but where, as will usually be the case, this rerolling mechanism is used in connection with a machine for forming and inserting the mouthpieces into the cigarette tubes, the rerolling mechanism will receive the shells directly from the mouthpiece inserting mechanism. In the particular construction shown in the drawings, which drawings illustrate one embodiment 70 of the invention, 1 indicates a part of the frame of the machine, this frame being provided with rods 2, 3 on which is supported a bracket 4. This bracket carries a cleft arm 5 which supports a slotted introducing tube 6, this tube coöperating with a cleft spindle 7 on which the mouthpiece blank is rolled, the blank being guided into the cleft in the spindle by a guide, as 8. The particular construction of introducing tube, 80 spindle and the parts immediately connected therewith is fully shown in an application filed by S. I. Prescott, Serial No. 316,686, of which the present application is 85 a division, and reference is made to said application No. 316,686 for a full disclosure 90 thereof.

When, as has been indicated, the rerolling mechanism hereinafter described is to form a part of, or be used in connection with, an 95 organized machine for forming and inserting mouthpieces, the shells, after having the mouthpieces inserted therein, will be delivered to the rerolling mechanism in any suitable way. In the particular construction illustrated, the rerolling mechanism includes an inclined table, as 9, on which the shells are dropped after the mouthpieces have been inserted therein.

The particular construction of the re- 105 rolling devices may be varied widely. As shown, they include a rerolling roll 10, this roll being provided with circumferential ribs 11 and coöperating with a curved bed, as 12, of which the table 9 may form a part. 110

These ribs 11 are so positioned with respect to the curved bed that the distance from the surface of the ribs to the bed is slightly less than the diameter of the cigarette tube and 5 mouthpiece of the shell operated upon, so that the tube and mouthpiece will be slightly flattened as the shell passes between the roll and bed.

In the best constructions embodying the 10 invention, means will be employed for straightening the shells, so that when they are acted upon by the rerolling means their axes will lie at right angles to the path of the shells through the rerolling means, or, 15 in other words, when the rerolling means includes a rerolling roll, the straightening devices will operate in such a way as to bring the axis of the cigarette shell into parallelism with the axis of the rerolling roll. 20 While the construction of these straightening means may be varied within wide limits, in the construction shown, the roll is provided with a segment-shaped block, as 13, this block having ribs which correspond 25 with the ribs 11 but which extend far enough from the surface of the roll so as to completely fill the opening between the roll and the bed 12, the outer surface of the ribs being curved to correspond with the curve of the 30 bed. The operation of these straightening means will be well understood from Figs. 4, 5 and 6. Fig. 4 represents a shell resting against the straightening block, the shell having been dropped upon the inclined table 35 9 and having rolled down it. As the roll rotates, the block moves from the position shown in Fig. 4 to the position shown in Fig. 5, during which time the action of gravity and the block causes the cigarette 40 shell to assume a position parallel to the axis of the rerolling roll. In Fig. 6, the block is shown as having moved far enough to permit the shell to enter the rerolling channel, that is, the space between the rerolling roll 45 and the bed 12. It may be remarked that the ribs are flattened slightly, as indicated at 14, thus insuring that the shell enters the rerolling channel.

While the action of gravity might be depended upon to cause the shells to enter the rerolling channel, in the best constructions embodying the invention means will be employed for positively forcing or inserting them thereinto. In the construction illustrated, these means include a curved arm 15, secured by clamps 16 to a rock shaft 17. This introducing arm, when employed, may be operated in any suitable manner. As illustrated, the shaft 18 of the rerolling roll

is provided with a cam disk 19 and the shaft 60 17 is provided with an arm 20 which is forced against the circumference of the cam disk by a spring 21. As the roll rotates and at the proper time, the arm 20 is forced by its spring 21 into the depression 22 of the 65 cam disk, this operation throwing the introducing arm forward and positively forcing the shell into the rerolling channel.

In order to operate the rerolling mechanism, the rerolling roll may be provided with 70 a gear, as 23, which gear will be driven from any suitable moving part of the machine with which this rerolling mechanism is connected.

The rerolled shells may be discharged into 75 any suitable receptacle, as, for instance, a magazine, indicated at 24, stripper fingers, as 25, being employed, if desired, to insure the delivery of the shells.

Changes and variations may be made in 80 the construction by which the invention is carried into effect. The invention is not, therefore, to be confined to the particular construction hereinbefore described and illustrated in the accompanying drawings. 85

What is claimed is:—

1. The combination with rerolling devices including a roll, of a tube stop carried by the roll and operating to position the tube, and means for delivering tubes containing 90 mouthpieces thereto.

2. The combination with rerolling devices including a roll, of a stop segment carried by the roll, and an inclined path down which the tubes containing mouthpieces roll against 95 the segment, whereby the tubes are properly positioned before they are acted upon by the rerolling devices.

3. The combination with rerolling devices of means for delivering tubes containing 100 mouthpieces thereto, means for positioning the tubes with their axes at right angles to their path of movement through the rerolling devices, and means for positively inserting the tubes into the rerolling devices. 105

4. The combination with rerolling devices including a roll, of a stop segment carried by the roll and operating to position the tubes, an inclined path down which the tubes containing mouthpieces move against the 110 segment, and a tube inserting means.

In testimony whereof, I have hereunto set my hand, in the presence of two subscribing witnesses.

SYDNEY I. PRESCOTT.
